CLAIM

The ornamental design for the combined portable fan and spray misting device, as shown.

DESCRIPTION

FIG. 1 is a perspective view of the combined portable fan and spray misting device showing our new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a left side view thereof;
FIG. 7 is a right side view thereof; and,
FIG. 8 is a perspective view of the portable fan portion of the claimed design shown separately for clarity of illustration.
